MINE CASE AND INSTRUMENT MOUNTING SYSTEM

Charles C. Vogt, Bethesda, and Howard W. Semon, Silver Spring, Md., assignors to the United States of America as represented by the Secretary of the Navy
Original application Feb. 6, 1953, Ser. No. 335,614, now Patent No. 2,947,249, dated Aug. 2, 1960. Divided and this application Feb. 29, 1960, Ser. No. 11,933

3 Claims. (Cl. 174—59)

(Granted under Title 35, U.S. Code (1952), sec. 266)

The invention described herein may be manufactured and used by or for the Government of the United States of America for governmental purposes without the payment of any royalties thereon or therefor.

This invention relates to an instrument mounting rack and more particularly to a rack which is adapted to house the various electrical components which are employed in the firing circuit of a mine.

This application is a division of our copending application, Serial No. 335,614, filed February 6, 1953, now matured into U.S. Patent No. 2,947,249.

It is apparent that there are various components in a mine which are utilized in firing and sterilizing the mine. These components include magnetic, pressure, and acoustic firing mechanisms, arming and sterilizing switches, actuation counters and batteries. Heretofore, these various components have been individually assembled within the mine casing and it has frequently been necessary to alter the interior design of the mine casing itself when varying the combination of components used. This system has certain disadvantages in that the mine firing system lacks flexibility so that it is difficult to vary the actuating components of the mine and further in that the mine is difficult to assemble and to test. For these reasons it has been found desirable to provide a rack which will house all the components necessary for actuating the mine and to construct these components of uniform size and shape so that they may be readily substituted to build up different combinations of actuating mechanisms in the mine.

This has been accomplished by the device herein disclosed wherein there is provided a rack having a portion thereof adapted to mount certain of the firing components of the mine and an additional space to be employed for housing the batteries used in the firing circuit of the mine. The units employed are of uniform dimensions so that they may be readily substituted whereby, for example, a mine designed for acoustic actuation may be easily assembled in place of a mine designed for magnetic actuation. In this manner a means is provided for assembling the electrical components of a mine firing system which is readily adapted for any operational requirement and which can be easily assembled and tested.

An object of this invention is to provide a rack for mounting the various electrical components of a mine.

A further object of this invention is to provide a rack for housing the electrical components of a mine in which the components may be assembled in any desired combination without the necessity for employing special mounting means for the various components.

An additional object of this invention is to provide a housing for the components of a mine firing circuit which is independent of the mine casing whereby the electrical circuit may be easily tested before assembling the housing within the mine casing.

Other objects and many of the attendant advantages of this invention will be readily appreciated as the same becomes better understood by reference to the following

2

detailed description when considered in connection with the accompanying drawings wherein:

FIG. 1 is a perspective view of one embodiment of the invention described herein;

FIG. 2 is an end elevation partly in section of the rack shown in FIG. 1; and

FIG. 3 is a perspective view of the tail section of a mine casing showing the mounting means for the rack of FIGS. 1 and 2.

Referring now to FIGS. 1 and 2 of the drawing there is disclosed an embodiment of the present invention in which the individual components are not separately mounted on the rack but are held therein by means of retaining walls. There is provided an upper compartment 13 and a lower compartment 14 each of which is composed of a top and bottom section suitably secured together. The upper compartment is composed of side plates 16 and 17 which are provided with flanges 18 and 19 respectively. A channel-shaped cover member 21 is secured to the side plates as by bolts 22. The top compartment is additionally provided with an end plate 23 as shown and a similar end plate is provided on the opposite end of this compartment. These end plates are suitably welded to the side plates 16 and 17. There is provided a bottom plate 24 (FIG. 2) which is provided with flanges 26 and 27 which are aligned with the flanges 18 and 19 respectively and apertures are provided in these flanges for the reception of bolts 28 which secure the top and bottom plates together.

The bottom compartment 14 is provided with a top plate 29 having flanges 31 and 32. The bottom plate 33 of this compartment has flanges 34 and 35 in alignment with flanges 31 and 32 respectively. Registering apertures are provided in these flanges for the reception of bolts 36. The lower compartment is provided with an end plate 37 suitably welded to the bottom plate, the other end of the compartment having a similar end plate. There is further provided on the ends of the compartments a member 38 having projections 39 which are in alignment with the flanges of the top and bottom compartments. These projections are welded to the flanges 26, 27, 31 and 32 so that the entire assembly is rigid.

It can be seen that the securing flanges of the upper and lower compartments form channels therebetween and within these channels are welded mounting brackets 41 and 42. In FIG. 3 there is shown the tail end of a casing 43 of a mine. Within this end section there is provided mounting bars 44 and 45 which are suitably secured to the mine casing. Suitably welded between the outer ends of these bars is a mounting plate 46 having bolts 47 thereon. The channel between the flanges on one side of the rack fits over bars 44 and 45, bolts 47 engaging apertures in mounting plate 41 and the apertures in plate 42 engage bolts 48 on plate 49 which is mounted between bars 51 and 52 whereby the entire assembly is rigidly held within the mine casing.

Within the upper compartment 13 of the instrument housing are located various components such as shown at 53 and 54 having jacks 55 for electrical connection.

It can be seen that the channel cover member 21 provides a space within which the wiring may be located. The lower compartment houses the batteries for the firing circuit of a mine. It can be seen that by this construction a means is provided whereby the various firing components of a mine may be readily varied to suit any desired operational requirement.

Obviously many modifications and variations of the present invention are possible in the light of the above teachings. It is therefore to be understood that within the scope of the appended claims the invention may be practiced otherwise than as specifically described.

What is claimed as new and desired to be secured by Letters Patent is:

1. In combination with a mine casing having means for removeably securing an instrument housing, said instrument housing having an upper compartment and a lower compartment for housing electrical components, each of said compartments having top and bottom portions, an end plate secured at each end of the top portion of said upper compartment, and an end plate secured at each end to the bottom portion of said lower compartment, fastening means removeably securing said housing to said mine casing, said top portion of said upper compartment being provided with electrical terminals therein, and a channel shaped member being removeably secured to the top of the upper compartment over said electrical terminals whereby a passage for connections to the electrical components is provided.

2. In combination with a mine casing having means for removeably securing an instrument rack for electrical components, said instrument rack comprising an upper compartment having flanged upper and lower portions, the flanges of the upper and lower portion of said upper chamber being removeably secured together, a lower compartment having flanged upper and lower portions, the flanges of the upper and lower portions of said lower compartment being removeably secured together, means securing the lower portion of said upper compartment to the upper portion of said lower compartment, fastening means mounted between said flanges removeably fastening said rack to said casing, the top portion of said upper compartment being provided with electrical terminals therein, and means providing a channel on top of said rack for the passage of electrical connectors whereby

said electrical components may be connected to external circuits.

3. In combination with a mine casing having means for removeably securing an instrument rack therein, said instrument rack comprising an upper compartment and a lower compartment, each of said compartments having an upper flanged portion and a lower flanged portion removeably secured together, means securing the top portion of said lower compartment to the lower portion of said upper compartment whereby said rack is made into an integral unit, electrical components disposed within said rack, mounting means in said rack removeably fastening said instrument rack to said mine casing, and means forming a channel on the top portion of said upper compartment for providing a passage for electrical conductors, and terminal means on the top portion of said upper compartment for connecting said electrical conductors to electrical components disposed within said instrument rack.
